SEWING MACHINE ATTACHMENT

**Edward C. Shoup and Sybil A. Hollcraft,
Riverside, Calif.**

Application January 24, 1938, Serial No. 186,737

2 Claims. (Cl. 117—1)

This invention relates to improvements in sewing machine attachments, and has particular reference to a device for twisting material.

The principal object of this invention is to produce a device of this character that can be readily attached and detached from a sewing machine, and a device which will accommodate the material being twisted after the twist has been completed.

10 A further object of the invention is to produce a device of this character which is simple to manufacture, easy to apply and one which may be quickly removed when the operation has been completed.

15 Other objects and advantages will be apparent during the course of the following description.

In the accompanying drawings forming a part of this specification and in which like numerals are employed to designate like parts throughout the same.

Fig. 1 is a side elevation of our device, as the same would appear when attached to a sewing machine;

Fig. 2 is an end elevation of Fig. 1.

25 Fig. 3 is a cross sectional view taken on the line 3-3 of Fig. 1.

Fig. 4 is a side elevation of our device, showing the spool in cross section and partly removed:

Fig. 5 is an enlarged fragmentary detail view, 30 showing the manner in which the twisted material is attached to the spool:

Fig. 6 is a modified form of our device.

Fig. 7 is an end section of our device, looking from the left hand end thereof:

35 Fig. 8 is a modified form of our device, showing the sliding clips; and

Fig. 9 is an end view

There are many times when it is advantageous

40 There are many times when it is advantageous to twist material to form braid, carpet material and the like. This is sometimes done by fasten-

45 This is sometimes done by fastening the ends of material to be twisted to a door-knob or similar fastening point, and to then twist the material by hand gradually walking away from the starting point as the twisted portion increases in length. This is a very tedious

creases in length. This is a very tedious process, and does not give a uniform twist, and, therefore, we have produced a device that can be attached to the ordinary sewing machine hand wheel, and by rotating this hand wheel through the customary movement of the sewing machine, we are enabled to easily and accurately twist material to any desired length and with a minimum amount of effort.

In the accompanying drawings wherein for the purpose of illustration is shown a preferred embodiment of our invention, the numeral 5 designates the hand wheel of an ordinary sewing machine. Some of these hand wheels have a groove in the outer surface thereof, over which a belt runs, or in some instances, the electric driving motor may drive through the wheel contacting the rim of the wheel. We have, therefore, provided four openings 6 through the wheel, which openings receive the hooked ends 7 of arms 8 which are formed of four strands of wire twisted together, as at 9, and then formed with parallel sections 11, and then further twisted together, as at 12. The parallel sections 11 engage the inner surface of the spool hub 13. (See Figs. 3 and 4). This spool hub is provided with ends 14 and 16 and thus form an ordinary spool. A slot 17 is formed in the end 14, and a hook 18 is secured adjacent thereto. When the spool is entirely upon the device the twisting point 12 projects beyond the outer surface of the spool of the end 14.

In the modified forms shown in Figs. 6 and 7, the construction is identical with the exception that the hooked ends 7 of Fig. 1 are reversed, so that they engage the outer periphery of the wheel 5, as indicated at A. The same numerals have been applied for the remaining parts. 25

In the modified form shown in Fig 8, the only difference is that we use sliding clips 19 instead of the wire hooks 7, and employ a twisting point B which corresponds to the twisting point 12 of the preferred form of our invention. 30

In use the device is attached to a fly wheel of a sewing machine, and the material to be twisted, as for instance the cord C of Fig. 5, is hooked over the hook 18 and brought through the slot 17 and into engagement with the twisting point 12. The machine is then started, and as a rule, the cord C will be twisted upon itself between the end of the spool and the point where it is being held by the fingers. As soon as this occurs, the operator leaves the twisted part upon the spool and then proceeds with a further twisting operation. Thus by rapid twisting a long length of twisted material may be easily formed.

It is to be understood that the form of our invention herewith shown and described is to be taken as a preferred example of the same and that various changes relative to the material, size, shape and arrangement of parts may be resorted to without departing from the spirit of the invention or the scope of the subjoined claims. 55

Having thus described our invention, we claim:—

1. In a device of the character described, a spool, means for securing said spool to a rotating member and in axial alignment therewith, said spool having a twisting point connected thereto and extending therefrom and in axial alignment with said spool, and means for holding material to be twisted by said spool, whereby rotation of said spool will effect a twisting of the material.
- 10 2. In a device of the character described, a plu-

rality of wires secured one to the other, said wires having arms diverging and terminating in hooked extremities, the opposite ends of said wires extending in parallel relation and having their free ends in turn twisted together, whereby a spool mounted on said parallel portions will be held thereon, whereby rotation of said spool may be effected.
